AUTOMOBILE

Harley J. Earl, Grosse Pointe Farms, Mich., assignor to General Motors Corporation, Detroit, Mich., a corporation of Delaware

Application January 4, 1954, Serial No. 28,313

Term of patent 7 years

(Cl. D14—3)

Fig. 1 is a side elevational view of an automobile embodying my new design with the side opposite being similar to that shown; and

Fig. 2 is a front view of the automobile of Fig. 1.

The dominant features of my design reside in the full line portions of the drawing.

I claim:

The ornamental design for an automobile, substantially as shown and described.
